UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-THREAD CONTROLLER FOR SEWING MACHINES.

Application filed November 27, 1922. Serial No. 603,504.

To all whom it may concern:

Be it known that I, LANSING ONDERDONK, a citizen of the United States, residing at New York, in the county of New York, 5 State of New York, have invented certain new and useful Improvements in Looper-Thread Controllers for Sewing Machines, of which the following is a description, reference being had to the accompanying drawing and to the figures of reference marked thereon.

The invention relates to new and useful improvements in looper thread controllers for sewing machines, and more particularly 15 to a thread controller for a looper mounted to oscillate in a horizontal plane.

An object of the invention is to provide a thread controller for a looper mechanism of the above type, which thread controller is 20 actuated directly from the looper and is given movements so as to take up slack during the first part of the forward movement of the looper, give up slack to the looper after it enters the needle thread loop 25 and while it is moving to the forward end of its stroke, again take up slack on the first part of the retracting movement of the looper until the needle is well into the looper thread loop, and then take up slack while 30 the looper is moving to the rear end of its stroke.

In the drawings—

Figure 1 is a bottom plan view of a portion of a sewing machine embodying my 35 improvements;

Fig. 2 is a top plan view of the looper and the thread controller therefor;

Fig. 3 is a plan view showing the position of the parts when the looper is at the 40 rear end of its stroke;

Fig. 4 is a similar view but with the looper at the point of entering the needle thread loop, and

Fig. 5 is a similar view but with the looper 45 at the forward end of its stroke.

The sewing machine to which my invention is applied includes a work support 1 of the usual construction having an opening 2 at the side of the throat plate. 50 Beneath the work support there is a bracket 3 in which is mounted a shaft 4 carrying a looper 5. The shaft 4 is provided with a laterally projecting arm to which a link 6 is connected, and this link 6 in turn is connected to a lever arm 7 pivoted at 8 to the

under side of the work support 1. The lever arm 7 is oscillated by means of a link 9. As this link 9 is moved back and forth, the lever arm 7 and link 6 move into and out of alinement, and thus impart oscillations to the looper giving an extended dwell to the looper while the same is at the forward end of its stroke. This looper mechanism per se, forms no part of the present invention, but is shown, described and 60 claimed in my prior Patent No. 1,123,578, granted January 5, 1915.

The present invention is directed to a thread controller for this horizontally moving looper which has an extended dwell at 70 the forward end of its stroke. The thread controller consists of an oscillating arm 10 pivoted at 11 to the work support. The looper carrier is provided with a laterally projecting arm 12 which of course, oscillates with the looper. A link 13 is pivoted at 14 to this laterally projecting arm 12 and is pivoted at 15 to the oscillating thread controlling arm 10. On the outer end of the arm 10 there is a thread eye 16. Secured to the under part of the work support 1 is a thread eye 17. This thread eye 17 is secured to the work support by means of a screw 18. The looper thread is indicated at 75 1 and passes from the supply through the thread eye 16 and to the looper. As clearly shown in Figures 3 and 4 the link 13 and arm 12 are substantially in alinement when the point of the looper is 80 entering the needle thread loop. Figure 5 shows the looper at the extreme forward end of its stroke and this arm and link have moved out of alinement and moved the thread controlling arm 10 to the left of 85 the position shown in Fig. 2. As the looper retracts just as the point of the looper is leaving the needle thread loop, the link and arm again come into alinement, and as the looper moves to the rear end of its stroke, 90 the arm and link move out of alinement as shown in Fig. 3, and again the thread controlling arm 10 is moved to the left of the position shown in Fig. 2. When the thread controlling arm is in the position shown in 95 Fig. 2, it has reached its maximum movement away from the thread eye 17.

It will be noted from the above, that as the looper starts from the position shown in Fig. 3 and moves toward the position 100

shown in Fig. 4, the thread controlling arm will take up slack in the looper thread and thus avoid any slack thread forming in front of the looper which might buckle and cause the looper to miss the needle thread loop. As soon, however, as the looper reaches the needle thread loop and starts to enter the same, the thread controlling arm ceases its slack take up movements and begins to give up slack so that the looper has sufficient slack thread to move to the forward end of its stroke without any undue strain on the looper thread. As the looper begins its retracting movement, the thread controlling arm moves toward the position shown in Fig. 4, and will take up slack so that the looper thread is kept substantially taut until the point of the needle has well entered into the looper thread loop. After the needle thread loop has been shed from the looper, then the slack in the thread is taken up preparatory to the next forward movement of the looper. It will be noted that the thread controlling arm is operated from the looper, and only moves when the looper is moving, and therefore, when the looper is at the forward end of its stroke and at a dwell, the thread controlling arm will also be at a dwell. I have provided, therefore, a thread controlling mechanism which is substantially idle when the looper is at a dwell, which receives all its movements from the looper and which has two slack take-up movements to each complete oscillation of the looper.

It is obvious that minor changes in the details of construction and the arrangement of parts may be made without departing

from the spirit of the invention as set forth in the appended claims.

40

Having thus described the invention, what I claim as new and desire to secure by Letters-Patent, is—

1. The combination with a looper carrier mounted to oscillate back and forth, a looper mounted in said carrier, means for imparting oscillations to said looper carrier and giving an extended dwell thereto at the forward end of the stroke of the looper, an arm projecting from the carrier, a thread controlling lever mounted at one side of the looper to oscillate in a plane parallel with the plane of oscillation of the looper, a link connecting said thread controlling lever with the arm of the looper carrier, said arm and link being so disposed as to move into alinement when the point of the looper is entering or leaving the needle thread loop.

45

2. The combination with a looper mounted to oscillate back and forth in the same path and in a horizontal plane, means for imparting oscillations to said looper and giving an extended dwell thereto at the forward end of its stroke, an arm projecting from the carrier for the looper, a thread controlling lever mounted at one side of the looper to oscillate in a horizontal plane, a link connecting said thread controlling lever with the arm of the looper carrier, said arm and link being so disposed as to move into alinement when the point of the looper is entering or leaving the needle thread loop.

50

60

65

In testimony whereof, I affix my signature.

LANSING ONDERDONK.
